SANDER

Stephen R. Teager, Canton, Ohio

Application October 8, 1943, Serial No. 505,482

1 Claim. (Cl. 51—273)

This invention relates to woodworking machinery and particularly to means for collecting dust generated by the action of abrading or other cutting elements upon the surface of the work.

The invention has for an object to utilize the main driven element of the machine to create a suction that creates an air stream that envelops the surface of the work being acted upon by the machine to sweep all dust created by the abrasive or other cutting implement into a suitable collector and prevent contamination of the air adjacent the machine.

A further object of the invention is to provide a dust collecting device that adds but little to the cost of the machine, which occupies a small amount of space and which is highly efficient in operation.

With the above and other objects in view the invention may be said to comprise the device illustrated in the accompanying drawing, hereinafter described and particularly set forth in the appended claims together with such variation and modification thereof as will be apparent to one skilled in the art to which the invention pertains.

Reference should be had to the accompanying drawing forming a part of this specification in which:

Figure 1 is a side elevation of a sanding machine embodying the invention;

Figure 2 is a front elevation of the machine shown in Fig. 1.

Figure 3 is a section taken on the line indicated at 3—3 in Fig. 2.

Figure 4 is a fragmentary detailed view showing a portion of the sandpaper locking ring.

Figure 5 is a side elevation showing the invention applied to a lathe.

In the accompanying drawing, the machine of the present invention is shown mounted upon a work table 1 which has a work support 2 mounted thereon adjacent one end to which is attached a blower casing 3, the casing 3 being secured to the work support 2 by means of bolts 4. The blower casing 3 has a tangential outlet 5 and a rear wall 6 upon which is mounted a motor 7 that has a shaft 8 which extends into the casing 3. The casing 3 has a front wall 9 provided with an opening 10 of substantially circular form and disposed concentrically with respect to the shaft 8. The shaft 8 carries a drum 11 within the casing 3 and this drum has a hub portion 12 attached to the shaft 8 as shown in Fig. 3 and provided adjacent its inner end with a projecting flange 13 to which is attached an inner fan forming

section 14 of the drum. The section 14 may be in the form of a one piece casting, the body portion of which is in the form of a flat disk attached to the flange 13. The section 14 has a cylindrical forwardly extending flange 15 together with curved fan blades 16 extending outwardly from the flange 15 and integral with the disk and flange. The drum 11 has a front section that has a flat face 17 that bears against the forward end of the hub 12 to form the front wall of the drum and a cylindrical flange 18 that fits within the cylindrical flange 15 of the fan section 14. The flanges 15 and 18 are secured together by means of rivets 19 and the outer face of the front wall 17 of the drum lies substantially in the plane of the front face of the wall 9 of the fan casing. The drum 11 is of a diameter such that the portion thereof extending into the opening 10 forms a narrow annular slot 20 between the periphery of the drum and the margin of the opening 10.

The shaft 8 is the main driven shaft of the machine being a rotating support either for a cutting element or for a piece of work. In the modification shown in Figs. 1 to 4, the shaft 8 serves as the spindle of a cutting element in the form of an abrasive disk, while in Fig. 5 the shaft serves as the rotary work supporting spindle of a lathe.

The cutting element may be in the form of a sandpaper facing 21 for the front wall 17 of the drum 11 and this sandpaper facing may be secured to the drum by means of a clamping ring 22 slidably mounted upon the drum periphery forwardly of the fan blades 16 which are offset inwardly from the front end of the drum. The ring 22 has one or more bayonet slots 23 that receive lugs 24 projecting from the periphery of the flange 18.

As shown in Figures 1 and 2 the work support 25 may be provided with a horizontal plate 25 that extends across the front wall of the supporting casing somewhat below the axis of the drum 11 to provide a support for pieces of work being abraded by the action of the abrasive facing on the drum 11.

A suitable dust collector which may be in the form of a filter cloth bag 26 is attached to the tangential outlet 5 of the fan casing which may be directed downwardly to position the collector beneath the table and serves to strain the dust from the air blown through the wall thereof. The dust collector 26 may be provided with a detachable bottom 27 that enables the filter bag to be emptied and cleaned. The motor, drum and suction fan are mounted as a unit in the cas-

ing 3, the motor housing having an attaching plate 28 serving as a closure for an opening in the rear wall of the casing through which the drum and fan are passed upon insertion into or removal from the casing.

In the modification shown in Fig. 5, and the casing fan and drum may be identical with the corresponding elements shown in Figs. 1 to 3, the casing 3 being attached to a bracket 30 at the end of the work table. The shaft 8, in this instance, serves as a work supporting and driving spindle having a work engaging dog 31 which cooperates with a center 32 carried by a tail stock 33 to rotatably support the work.

In both of the modifications disclosed a strong current of air envelops the exposed surface of the work and flows axially of the rotating drum into the annular slot 20 and through the fan blades 16 and outlet 5 to the dust collector 26. Particles dislodged from the surface of the work and thrown outwardly by centrifugal force are entrained by the swiftly moving air stream and carried through the fan casing to the dust collector.

It is apparent that the device of the present invention involves but a slight additional expense in the construction of the wood working machine and provides a very compact dust collecting unit which does not increase the floor space required for the machine. Furthermore the provision of a rapidly moving column of air en-

longer than the 10-year period of the old law, and will be paid in quarterly installments over a period of 10 years. The amount of the loan will be determined by the amount of the original loan, the rate of interest, and the time period of the loan.

veloping the surface of the work being acted upon provides a very effective barrier against the passage of the dust from the surface of the work into the atmosphere of the room in which the machine is located.

It is to be understood that variations and modifications of the specific device herein shown and described for purposes of illustration, may be made without departing from the spirit of the invention.

What I claim is:

In a machine of the character described, a supporting table, a blower casing mounted on said table said casing having a tangential outlet, a front wall provided with a substantially circular opening and a rear wall spaced from the front wall, a shaft extending into said casing concentric with said opening, a drum fixed to said shaft and projecting into said opening, said drum having a front end substantially in the plane of the front face of said casing and a peripheral portion within the opening and forming therewith a narrow annular air inlet slot, fan blades mounted upon the exterior of the drum and spaced inwardly from the front end thereof, a lug projecting from the periphery of said drum, and a sandpaper clamping ring mounted on the periphery of said drum between said blades and the front end of the drum, said ring having a bayonet slot to receive said lug.
